UNITED STATES PATENT OFFICE.

SAMUEL KOFF, OF NEW YORK, N. Y.

BOX.

Application filed February 5, 1928. Serial No. 86,321.

The present invention relates to boxes made from paper, cardboard or similar material, more especially folding blank boxes, and it is the object of the invention to provide a 5 folding or collapsible box of novel and improved construction, which may be made from a single blank, and which will be strong in construction and efficient in use.

With the foregoing and other objects in 10 view, which will be apparent as the description proceeds, the invention resides in the construction and arrangement of parts, as hereinafter described and claimed, it being understood that changes can be made within 15 the scope of what is claimed, without departing from the spirit of the invention.

The invention is illustrated in the accompanying drawings, wherein—

Figure 1 is a perspective view of the box 20 in erected or open position.

Fig. 2 is a plan view of the box when folded.

Fig. 3 is a plan view of the blank from 25 which the box is made.

Fig. 4 is a perspective view corresponding to Fig. 1 illustrating a modified form of box.

The box is conveniently and economically constructed from a rectangular blank, as seen in Fig. 3, and comprises the bottom 7, side 30 walls 8 and end walls 9. The side walls 8 have flaps 10 at their ends folded inwardly and overlapping the inner surfaces of the end walls 9, and the end walls 9 have lips or portions 11 at their upper edges that are 35 folded inwardly against the inner surfaces of said end walls. The flaps 10 occupy the corner portions of the blank between the ends of the walls 8 and 9, and said flaps 10 are of a length equal to the aggregate length of one 40 end wall 9 and its lip 11. As shown in Figs. 1 and 2, the ends of the flaps 10 overlap midway between the side walls.

Each flap 10 has a slit or cut 12 extending 45 downwardly from its upper edge to a point between the upper and lower edges of said flap, and the slit 12 is spaced a distance from the corresponding end of the side wall 8 less than the height of the walls. As shown, the distance between the slit 12 and the corresponding end of the side wall is about one-half the height of the walls. The flap 10 has an oblique or inclined fold line 13 extending 50 from the lower end of the slit 12 to the corresponding corner of the bottom 7. The slit 12 and fold line 13 define a locking portion 55 14 extending upwardly along the correspond-

ing end of the side wall from the fold line 13 to the upper edge of the flap 10.

• The upper edge portions of the flaps 10 beyond the slits 12 overlap the inturned lips 11 substantially flush with the bends between the end walls 9 and their lips 11, and staples 15 or other securing means are engaged through the upper edge portions of the flaps 10, lips 11 and end walls 9, thereby securing 60 them together firmly, with the portions 14 free. The flaps 10 are preferably secured by other staples or securing elements 16 to the end walls 9 below the lips 11 and near the bottom of the box. The flaps 10 stiffen and 65 strengthen the end walls, and it will be noted that the upper portions of the flaps 10 are secured to the upper edge portions of the end walls 9 throughout the greater portions of the lengths of the end walls, excepting at the 70 corners of the box where the portions 14 are located. The corners at the open ends of the slits 12 are preferably cut away, as at 17, to 75 avoid sharp corners and to facilitate the folding and opening of the box.

When the box is erected or opened the end 80 portions of the lips or flaps 11 which project from between the stapled portions of the flaps 10 and end walls 9 are snapped over the upper ends of the portions 14, as seen in Fig. 1, thereby holding the box in erected position. This provides a firm and strong 85 box, and it will be noted that the fold lines 13 extend only part way upward from the bottom of the box and terminate a distance 90 below the upper edges of the end walls. The lines of the folds 13 intersect the upper edges of the walls 9 at distances inwardly beyond the slits 12, so that said slits are located 95 between said points of intersection and the corners of the box. The flaps 10 may thus be secured to the lips 11 and end walls 9 comparatively close to the corners of the box.

By pressing outwardly on the end walls, 100 the box is readily folded, the end walls swinging outwardly and the side walls inwardly, as seen in Fig. 2. The end portions of the lips 11 snap from over the portions 14, to permit the portions 14 to swing 105 into the planes of the side walls 8, while the remaining portions of the flaps 10 remain flatly against the end walls. The intermediate portions of the lips 11 and those portions of the flaps 10 beyond the slits 12 are 110 secured permanently to the end walls 9 with the lips 11 clamped between said end walls

and flaps. This enables the lips 11 to bear snugly against the end walls 9, and, furthermore, the lips 11 being clamped between the flaps 10 and end walls 9 are prevented from being torn loose from the end walls 9. Furthermore, this arrangement will confine the springing or flexing of the lips 11 to those portions thereof which are located between the slits 12 and side walls 8, thereby providing a strong and substantial construction.

The box shown in Fig. 4 is of less height than the box shown in Fig. 1, so that the flaps 10 are shorter, and said flaps are therefore spaced apart at the ends of the box, instead of abutting or overlapping as shown in Fig. 1.

Having thus described the invention, what is claimed as new is:—

20 A box of cardboard or similar material comprising a bottom, side walls and end walls, the end walls having turned in lips at their upper edges and bearing against the inner surfaces of said end walls, the side walls having end flaps overlapping the inner

surfaces of the end walls, said flaps having slits extending downwardly from their upper edges at distances from the corresponding side walls less than the height of said walls, said flaps having inclined fold lines between the slits and corners of the bottom, the portions of the flaps beyond said slits extending upwardly and overlapping the intermediate portions of said lips with the lips located between said portions of the flaps and the end walls, and securing means engaging through said end walls, lips and portions of the flaps to clamp the lips between said portions of the flaps and end walls and to confine the flexing of the lips away from the end walls to those portions of the lips between said slits and side walls, the portions of the flaps at the upper ends of the slits above said fold lines being cut away to enable such portions to be engaged under the end portions of the lips when the box is erected.

In testimony whereof I hereunto affix my signature.

SAMUEL KOFF
